UNITED STATES PATENT OFFICE.

JOSEPH A. MILLER, OF HOPEDALE, MASSACHUSETTS, ASSIGNOR TO DRAPER CORPORATION, OF HOPEDALE, MASSACHUSETTS, A CORPORATION OF MAINE.

BOBBIN-CLUTCHING MEANS FOR ROTATABLE SPINDLES.

Application filed November 5, 1926. Serial No. 146,398.

This invention relates to that type of spindle employed in spinning frames and similar machines in which bobbin clutching members are provided to fit within the base of the bobbin and to expand therein thus to maintain the bobbin in position during the spinning or other operation.

The object of the present invention is to provide a simple and efficient form of construction which shall involve no loose parts or parts which as the result of usage, wear or accident may become loose or mispositioned.

The object of the invention is further to provide a construction which may be readily and economically manufactured and assembled.

The object of the invention is further to provide a construction which shall act both by resilient expansion preliminarily to grip and hold the bobbin and by centrifugal action finally to grip and hold the bobbin with great firmness during rotation in the spinning or other operation.

The object of the invention is further to provide a construction in which, if yarn be accidentally wound on the bobbin clutching elements or the blade, it may be readily slipped off therefrom without having to be cut.

The object of the invention is further to provide a construction which may readily be cleaned and the operation of which will not be practically interfered with by the presence of lint or fly.

The object of the invention is further to provide a construction in which the pressure of the bobbin clutching members shall be exerted symmetrically and evenly radially of the spindle.

These and other objects and features of the invention will appear more fully from the accompanying description and drawings and will be particularly pointed out in the claims.

As the general construction and operation of spinning and similar spindles with bobbin clutching members is well known and familiar to those skilled in the art, it will only be necessary here to illustrate and describe those parts directly concerned with the present invention. It will be recognized that spindles operate at a very high rate of speed, are subject to the collection of more or less

lint and fly thereon, to the accidental winding of yarn thereupon, and that the operation of placing and doffing the bobbins is performed by more or less careless operators. The construction must be such that the bobbin may be readily placed on and doffed from the spindle and at the same time the construction must be such that the bobbin will be securely gripped and firmly held when the spindle is rotating. These and the other conditions familiar to those skilled in the art render the bobbin clutching feature of the spindle one of the greatest importance.

In the drawings:

Fig. 1 is a side elevation of a portion of a spindle embodying a preferred form of the present invention.

Fig. 2 is a view chiefly in vertical cross section on the line 1—1 of Fig. 3 of the construction shown in Fig. 1.

Fig. 3 is a top plan view partially in horizontal cross section of the line 3—3 of Fig. 2 of the same construction.

In the preferred construction illustrated, the blade 1 of the spindle is of the usual form and has rigidly secured thereto, preferably by being driven tightly thereon, a whirl 2 of the usual type. The whirl 2 is provided with an upper flat surface 3 to form the rest for the bobbin when placed in running position.

The bobbin clutching feature of this invention in its preferred form is a very simple construction and consists of an integral one-piece metal sleeve formed to present a plurality of similar symmetrically located longitudinally extending bobbin clutching arms. This sleeve is preferably made of metal having some temper and resilience such, for example, as drill rod steel or stub steel, and the entire sleeve may readily be formed by the usual turning, drilling and sawing operations or upon an automatic screw machine.

One essential feature of the invention is that the bobbin clutching sleeve shall be rigid at its lower end with the spindle blade and the arms thereof movable at their upper ends both under the action of their own resiliency and the action of centrifugal force. This is secured by forming the arms as integral portions of a sleeve such as just referred to.

In the construction thus illustrated, the

sleeve is shaped to present an exterior surface which normally conforms substantially to, but is of slightly greater diameter than, the bore of the bobbin. The lower end of 5 the sleeve is shaped to present an exterior flange 4. An annular recess 5 concentric with the blade is formed in the upper surface of the whirl or bobbin rest and the flange 4 has a driving fit at its outer perim- 10 eter in this recess, thus securing the sleeve rigidly to the whirl and thus to the blade. The interior surface of the sleeve is spaced from the inner periphery of the recess 5, as shown at 6.

15 The bobbin clutching arms are preferably formed by splitting the sleeve longitudinally from its upper end nearly to the flange by cuts or kerfs 7, shown much enlarged, and there are thus formed a plurality of similar 20 arms symmetrically arranged around the blade and extending longitudinally thereof above the bobbin rest. The upper portion of the sleeve, and consequently the upper portions 8 of the bobbin clutching arms are 25 much thicker radially than the intermediate portion of the sleeve or the portions 9. This causes the upper portions of the arms to be much heavier than the intermediate portions or to be substantially weighted and 30 leaves the intermediate portions 9 of a substantially resilient nature. Consequently the bobbin clutching arms have a spring or yield radially of the blade due to the resiliency of the portions 9, and are also intensely responsive to centrifugal action due to the heavy 35 weighted upper portions 8.

The upper ends of the bobbin clutching members opposite the rigid or fixed ends are permitted inward movement toward the 40 blade but are limited as to outward movement so that they will not move out too far radially under centrifugal action if the spindle is rotated without a bobbin in place. This result is secured by a collar 10 driven 45 on the spindle and presenting a depending annular flange 11 slightly telescoping over thin upward projections 12 on the upper ends of the bobbin clutching arms.

The upper end of the sleeve is reduced 50 inwardly on a smooth curve and consequently the exterior upper surfaces of the bobbin clutching arms curve inwardly at 13 on the same smooth curve. This enables the bobbin readily to be placed in position and also 55 enables any mass of yarn accidentally wound on the bare bobbin clutching element to be slipped off over the end of the spindle without having to be cut.

The bobbin clutching members are all of 60 precisely the same shape and construction and this is necessary in order that they may act symmetrically in gripping and holding the bobbin. This result is insured in the preferred form of the present invention ill- 65 istrated because these bobbin clutching

members are formed from a sleeve which is first given the required shape or configura- 70 tion.

The operation of the spindle will now be apparent. The bobbin clutching members 75 normally stand as shown in Fig. 1, due to their original shape, with the exterior surface of the entire group conforming sub- 80 stantially to, but of slightly greater diameter than, the bore of the bobbin. When the 75 bobbin is placed on the blade and seated on the bobbin rest, the arms first act by yielding inwardly, due to the resilience of the portions 9, to engage the bobbin bore which slides down easily over the surfaces 13 and 80 this resilience is sufficient to hold the bobbin in place as the spindle starts rotating. As soon as the spindle is rotating, the centrifugal force exerted upon the heavy, 85 weighted free ends of the bobbin clutching members causes them to grip and hold the bobbin very firmly.

It will be seen that there are no loose parts 90 which can drop out or the operation of which can be interfered with in any way. The rigid positioning of the sleeve or the bobbin clutching arms at one end insures the relative position of the parts remaining constant. The only place at which lint or fly 95 can enter is through the slots 7 and as these are very small, and as the space within the sleeve or between the blade and the bobbin clutching members is relatively large, there is practically no chance of lint or fly collecting sufficiently to interfere with the operation. Any such collection may readily be 100 removed by blowing it out.

The entire construction may be readily 105 and economically manufactured and assembled.

Having thus described the invention, what 110 is claimed as new, and desired to be secured by Letters Patent, is:

1. A rotatable spindle comprising a blade, 115 a bobbin rest secured thereto, an integral one-piece bobbin clutching sleeve concentric with the blade having a cylindrical lower end rigidly secured in the bobbin rest and spaced from the blade, the said sleeve presenting a plurality of similar upwardly extending arms symmetrically arranged around the blade, said arms being much heavier at their upper free ends than at their intermediate portions and the intermediate portions being resilient, a collar on the blade cooperatively related to the arms to limit the outward, while permitting the inward, movement of the upper free ends of the arms, the said arms first acting yieldingly to engage the bore of the bobbin placed on the blade and seated on the bobbin rest and then, upon rotation of the spindle, acting by centrifugal force firmly to clutch the bobbin. 120

2. A rotatable spindle comprising a blade 125 and an integral one-piece spring metal sleeve 130

having a cylindrical lower end rigidly mounted concentrically of the blade and having its exterior surface shaped to conform substantially to, but of slightly greater 5 diameter than, the bore of the bobbin, the upper end portion of the sleeve being much thicker than an extended portion intermediate the ends, the said sleeve being split longitudinally through the thicker upper 10 end and intermediate portions to form a plurality of smooth bobbin clutching arms similarly resilient at their intermediate portions and similarly weighted and thereby intensely responsive to centrifugal action at 15 their free ends.

3. A rotatable spindle comprising a blade, a bobbin rest secured to the blade and having a concentric annular recess in its seat, an integral one-piece sleeve concentric with 20 and spaced from the spindle and shaped ex-

teriorly to conform to the bore of the bobbin and having at its lower end an exterior cylindrical flange tightly fitted in said recess and split longitudinally above the flange into a plurality of similar bobbin clutching 25 arms, the upper portion of the sleeve being much thicker radially than the portion intermediate it and the flange, thereby causing the arms to be substantially weighted at their upper portions and to present intermediate resilient portions, whereby when a bobbin is placed on the blade and seated on the rest, the said arms first act yieldingly to engage the bore of the bobbin and then, upon rotation of the spindle, act by centrifugal 30 35 force firmly to clutch the bobbin.

In testimony whereof, I have signed my name to this specification.

JOSEPH A. MILLER.
